COMBINED RADIO AND TELEVISION
ANTENNAWendell L. Carlson and Vernon D. Landon, Had-
donfield, N. J., assignors to Radio Corporation
of America, a corporation of Delaware

Application April 22, 1939, Serial No. 269,312

14 Claims. (CL 250—20)

This invention relates to noise reducing antenna systems and more particularly to a simplified arrangement adapted to provide improved reception within two distinct frequency bands, such as would be required for the reception of television and broadcast signals.

Among the objects of this invention are the provision of an improved and simplified noise reducing antenna system; the provision of an improved system for coupling a broadcast receiver, or the like, to a high frequency, or television antenna; the provision of a simplified system for coupling a low frequency receiver to a high frequency balanced antenna to provide noise reduction without unbalancing the high frequency antenna; and the provision of an improved antenna which is particularly adapted for use in such a system.

One known system for coupling a low frequency receiver to a balanced dipole arrangement is that in which the low frequency input circuit of the receiver is connected to the center tap of the high frequency balanced input winding. This arrangement makes necessary the provision of a tap or contact on the mid-point of the high frequency input winding. Such a tap necessarily involves an added expense in the manufacture of such a coil, and it is, therefore, desirable to provide a system which eliminates the necessity of such a tap.

Another known system is that in which the balanced antenna system is used as a dipole at high frequency, while for operation at low frequencies, a capacitor is connected between the receiver input and one or both conductors of the antenna transmission line. Obviously, such a system does not provide noise reduction for either low or high frequency reception because a single coupling condenser of this type tends to upset the balance in the high frequency system, so that its efficiency in reducing noise picked up in the transmission line is decreased. The use of two capacitors connected to both transmission lines makes possible more nearly balanced operation, but it is subject to the disadvantage that the coupling condensers by-pass the high frequency signals.

In accordance with this invention, therefore, a system is proposed in which a dipole antenna operating at high frequencies is connected through a balanced transmission line to the receiver, while for the lower frequencies, the antenna is made to operate as a capacity antenna by means of a connection from the low frequency input system to a shielding conductor

which encloses a substantial portion of the antenna down lead transmission line. In such a system the capacity of the line to the shield does not upset high frequency operation because the capacity is distributed over about one-half wavelength of line.

This operation will be better understood from the following description when considered in connection with the accompanying drawing. Similar reference numerals refer to similar parts throughout the drawing.

Referring to the drawing, Figure 1 illustrates an embodiment of this invention for use in connection with a broadcast receiver adapted to receive signals in two separate frequency ranges; Figure 2 illustrates a preferred embodiment of this invention in connection with a television receiver having facilities for the reception of normal short and long wave broadcasts; Figure 3 illustrates a modification of this invention; and Figure 4 represents the application of this invention to a coupling transformer which is adapted to be utilized in connection with any broadcast receiver.

Referring to Fig. 1, a dipole antenna 5 is connected to the input terminals 7 and 9 of a receiver 11 by means of a twisted-pair transmission line 13. Within the receiver, a high frequency primary 15 is connected to the high frequency input terminals 7 and 9. The receiver is also provided with a pair of low frequency input terminals 17 and 19. The primary 21 of a low frequency coupling transformer is connected across the low frequency input terminals 17 and 19. The secondary coil consists of two sections. The first section, 23, is coupled to the low frequency primary 21, while the second section, 25, is coupled to the high frequency primary 15. The two secondary windings are connected in series. A switch 27 is provided by which the low frequency secondary 23 may be short-circuited during reception on the high frequency band. A tuning condenser 29 is connected across both of the secondary windings. The grid of the first stage amplification is connected to the high frequency winding 25. The remainder of the receiver is conventional, and is not illustrated. In order to provide a leakage path to ground for static discharges, and the like, a resistor 31 is connected between the center tap or one side of the primary winding 15 and ground. The value of this resistor 31 is preferably of the order of 1 megohm, and consequently, it does not affect the balanced input system.

A conductive sheath 33, which may be a woven metallic braid, tubular conductor, or the like, encloses a substantial portion of the transmission line 13 and is connected to the low frequency input terminal 17. The capacity between this metallic braid or shield and the conductors of the transmission line is uniformly distributed along the line, and is substantially equal from the shields to each of the two conductors. The length of this conductive shield may be, for example, approximately 10 feet. While the conductive shield does not unbalance the high frequency system, it provides sufficient capacity coupling to the transmission line 13 so that low frequency signals may be received, the antenna functioning as a capacity antenna. While the low frequency system may be operated with a ground connection, to provide noise-free reception in the low frequency bands, a counter-poise 35 is provided, which is connected to the remaining low frequency input terminal 19 in the manner described in our copending application Serial No. 253,908, filed January 31, 1939, and entitled "Noise reducing systems." Locally generated noise is picked up on the counter-poise and on the down leads and applied to the primary coil 21 in phase opposition so that the noise-representing currents in the primary are substantially reduced. Voltages induced on the antenna 5 and upper portion of the transmission line 13, which are preferably located in a region free from locally generated noises, are transferred to the conductive sheath 33 and produce currents through the low frequency primary 21 in the well known manner.

The manner in which this invention is particularly advantageous for use in a television receiver is best illustrated by reference to Fig. 2. In order to provide the maximum gain at the ultra high television frequencies, it is desirable to provide a resonant primary circuit at all operating frequencies. Accordingly, a system has been proposed in which any one of a plurality of high frequency primary windings 37 may be selected by a switch 39. This arrangement permits each primary winding to be tuned to that frequency which is most advantageous for the particular operating range to which it corresponds. It is apparent that if the system is utilized in which a center tapped coil is necessary, that such an arrangement would require an additional section on the selector switch 39. This expense would, of course, be in addition to that involved in the provision of center-tapped coils. In the arrangement shown the conductive sheath or shield 33 makes unnecessary the use of center-tapped primary coils for the television section, and provides a satisfactory antenna for the reception of low frequency broadcast signals and for the reception of the usual high frequency broadcast signals. In such an arrangement, the transmission line 13 is connected to the television input terminals 41, 43, while the shield 33 is connected to the input terminal 45 which is the input connection to the usual low and high frequency receiver input system represented by the switch 47, and primary windings 49, 51. In this instance, a conventional ground connection is shown for reception at broadcast frequencies, although the counter-poise may be used in the manner shown in Fig. 1.

Since the system illustrated in Fig. 2 is particularly adapted for the reception of television signals, particular attention is directed to the antenna which is employed in order to provide max-

imum response over a wide range of frequencies. The preferred antenna arrangement consists of a pair of oppositely extending radiating elements 53 and 55, each of which consists of two parallel horizontal conductors a quarter wave long disposed in a vertical plane and spaced apart approximately $\frac{1}{16}$ of a wave length at the operating frequency. The conductors of each element are connected at their inner adjacent ends by a pair of jumpers or conductors 57, 59 which constitute a short transmission line. The spacing between conductors 57 and 59, and their diameters are selected so that the impedance of the line is approximately 200 ohms. The transmission line 13 preferably has a characteristic impedance approximately equal to 100 ohms, and is connected to the mid-point of the short transmission line 57, 59. It is apparent, therefore that the antenna essentially comprises two dipoles connected in parallel, and that the impedance, looking in either direction from the point of connection, is approximately 100 ohms, thus matching the impedance of the transmission line 13 to that of the antenna system. If it is desired to provide such an antenna with improved directional characteristics, a pair of reflector elements 61, 63 may be located in a plane parallel to the plane of the antenna and at a suitable distance to provide the desired characteristics. The distance between the antenna and the reflectors should be approximately $\frac{1}{4}$ of the average operating wave length.

The antenna illustrated in Fig. 2 is particularly useful within the television frequency range since its frequency response is approximately twice as broad as that of a single dipole antenna of similar construction.

In the embodiment of our invention illustrated in the preceding figures, the uniformly distributed capacity coupling to the transmission line has been provided by a conductive shield which encloses a portion of the line. An alternative arrangement is illustrated in Fig. 3, in which a third conductor 65, is included in a portion of the twisted transmission line. While this arrangement may be somewhat cheaper than that shown in the preceding figures, the coupling may not be quite as uniform along the line and its capacity per unit length may be somewhat less.

In each of the preceding illustrations, it has been assumed that the input circuits shown constitute a portion of the receiver itself, or, in the case of Fig. 2, a portion of two receivers. It is frequently desirable to provide a coupling transformer by means of which a receiver having only antenna and ground input connections may be connected to a dipole antenna to provide reception in different frequency ranges. A coupling transformer designed in accordance with this invention to accomplish this purpose is illustrated in Fig. 4.

A transformer unit 67 includes low and high frequency primary windings 69 and 71, respectively, which are coupled to corresponding secondary windings 73 and 75. Output terminals adapted to be connected to a receiver are connected to the outer terminals of the serially connected secondary windings. A capacitor 77 is connected across the low frequency secondary 73 and provides a shunt path for high frequency currents which are induced in the high frequency secondary. As before, a conductive shield 33 and a counter-poise 35 are connected to the low frequency input terminals.

We claim as our invention:

1. In a device of the character described, an

5 antenna, a receiver having at least two input circuits, a transmission line connected between one of said input circuits and said antenna, and means including a capacity element having a distributed capacity to said transmission line coupling said antenna to the other of said input circuits.

10 2. In a device of the character described, an antenna, a receiver having at least two input circuits, a transmission line connected between one of said input circuits and said antenna, and means including a capacity element coupling the other of said input circuits to said transmission line over a substantial portion of the length of 15 said line.

15 3. In a device of the character described, a dipole antenna, a receiver having at least two input windings, a transmission line connecting one of said windings to said antenna so that circulating currents pass through said winding in response to signal voltages on said antenna, and means including a capacity element having a uniformly distributed capacity to said transmission line coupling said antenna to the other of said 25 input windings.

30 4. In a device of the character described, a dipole antenna, a receiver having at least two input circuits, a transmission line connecting one of said circuits to said antenna so that circulating currents pass through said circuit due to the dipole action of said antenna, and means including a capacity element having a uniformly distributed capacity to a portion of said transmission line for coupling said antenna to the other of said circuits with respect to voltages due to 35 the capacity action of said antenna.

35 5. In a device of the character described, a receiver having at least two input circuits, a dipole antenna, a transmission line connecting said antenna to one of said input circuits, and means including a capacity element having a uniformly distributed capacity to said transmission line connected to the other input circuit.

40 6. A device of the character described in claim 5 in which said capacity element is a conductive shield surrounding but insulated from said line.

45 7. A device of the character described in claim 5 in which said capacity element is a conductor which is adjacent the conductors of said line and 50 insulated therefrom.

55 8. A noise reducing antenna system for operation in two distinct frequency ranges which includes a dipole antenna, an input transformer having at least two input windings, a transmission line connecting said antenna to one of said windings, and a conductive sheath around a portion of said line, said sheath being connected to the other input winding.

60 9. A noise reducing antenna system for operation in two distinct frequency ranges which includes a dipole antenna, an input transformer having at least two input windings, a transmission line connecting said antenna to one of said windings, a conductive sheath around a portion 65 of said line, said sheath being connected to one end of the other input winding, a counterpoise connected to the other end of said winding, at least two output windings, associated respectively with said input windings and connected in series, and a capacitor in shunt with the output

winding associated with the input winding to which said sheath is connected.

10 5 10. A noise reducing high and low frequency antenna system including in combination a dipole antenna, a receiver having an input system which includes a high frequency and a low frequency primary winding, said high frequency primary being connected to said dipole antenna by a transmission line, a conductive shield enclosing a substantial portion of said line and comprising a uniformly distributed capacity to said line for the transmission of low frequency signals from said antenna, said shield being connected to one terminal of said low frequency primary winding, and a counterpoise connected 15 to the other terminal of said low frequency primary winding.

15 20 11. A low and high frequency noise reducing antenna system including in combination a dipole antenna comprising a pair of oppositely extending elements, each of said elements comprising a pair of parallel conductors, the conductors of each element being connected at their adjacent ends by a pair of jumpers, a transmission line connected between the mid-points of said jumpers, a transformer having at least two input windings, one of said windings being connected to said transmission line, a conductive shield enclosing a substantial portion of said line and connected to the other of said input windings. 30

25 12. In a device of the character described, a dipole antenna comprising a pair of oppositely extending radiating elements, each of said elements comprising a pair of vertically disposed, parallel conductors spaced apart approximately one-tenth of a wave-length at the operating frequency, the conductors of said elements being connected at their inner ends by a pair of jumpers, and a transmission line connected between the mid-points of said jumpers. 40

30 45 13. In a device of the character described, a dipole antenna including a pair of oppositely extending radiating elements, each of said elements comprising a pair of parallel conductors spaced apart approximately one tenth of a wave-length at the operating frequency, the conductors of said elements being connected at their inner ends by a pair of jumpers, a reflector comprising a pair of conductors parallel to and coextensive with said elements and spaced therefrom a fraction of a wave-length, and a transmission line connected between the mid-points of said jumpers. 50

35 40 55 14. A noise reducing antenna system which includes a dipole antenna, a receiver having a plurality of high frequency input circuits corresponding to a plurality of operating frequencies in a high frequency band, and a low frequency input circuit, a transmission line, selector means, said line being connected between said dipole antenna and said selector means so that any desired one of said high frequency input circuits may be connected to said line, and a conductive shield enclosing a portion of said line comprising a uniformly distributed capacity coupling to said line, said shield being connected to one terminal of said low frequency input circuit. 60 65
